F. M. BALDWIN

SIGNALING DEVICE FOR VEHICLES

Filed Aug. 23, 1922

UNITED STATES PATENT OFFICE.

FREDERICK M. BALDWIN, OF LOS ANGELES, CALIFORNIA.

SIGNALING DEVICE FOR VEHICLES.

Application filed August 23, 1922. Serial No. 583,742.

To all whom it may concern:

Be it known that I, FREDERICK M. BALDWIN, a citizen of the United States, residing in the city of Los Angeles, county of Los Angeles, and State of California, have invented certain new and useful Improvements in Signaling Devices for Vehicles, of which the following is a specification.

My invention relates to signaling devices for vehicles of the character disclosed in my United States Letters Patent No. 1,326,127, issued to me December 23, 1919, and has for its principal object to provide certain improvements therein whereby said signaling device is more simple and economical in its construction, and more accurate in its operation.

In my present invention, I prefer to use the representation of a human hand as the signaling member, although this is not necessary, if another form of signal element is desired. I also prefer that the hand shall assume a vertical position as it is drawn back into the case or frame and that it shall assume a horizontal position when extended straight outwardly, an upwardly directed position when extended outwardly and upwardly, and a downwardly directed position when extended outwardly and downwardly, just as the human hand assumes when giving the three signals now quite commonly used for indicating turns to the right, or to the left, or a stop. I have also provided a simplified connection of the signaling element to the outer ends of the lazy tongs whereby said signaling element is automatically turned from the vertical to the horizontal position as it is extended outwardly by the extension of said lazy tongs. I have also provided an improved mechanism for operating the lazy tongs to extend them straight outwardly, or upwardly inclined or downwardly inclined, as may be desired, and for releasing them and returning them to normal, or retracted position.

In order to more fully explain my improvements, I have embodied them in the accompanying sheet of drawings for illustrative purposes and will describe the same.

Figure 1 is a view of a portion of the front part of an automobile with my improved signaling device mounted thereon and shown extended in an outwardly and upwardly inclined position in full lines, in an outwardly direction and in an outwardly

and downwardly inclined position in broken lines;

Figure 2 is an inside view of a mechanism for holding and releasing the operating cables;

Figure 3 is an edge view thereof;

Figure 4 is a horizontal sectional view through the case of the device, as shown in Fig. 5;

Figure 5 is a side view of the device, with the side removed and with parts broken away; and

Figure 6 is a back view of the signal hand with the lazy tongs attached.

Referring in detail to the drawings, I provide a small case, 1, to be mounted at some convenient position, as at the side of the windshield frame of an automobile, as shown in Fig. 1. Within said case is mounted two discs, or operating elements, 2 and 3, rotatably mounted to turn on an axis, 4, in opposite directions, each element being provided with an operating cable, as 5, resting around a grooved and curved member 6, attached to the side of each disc, and in which the operating cable runs. The discs are also provided with radially extending fingers, 7 and 8, to which the inner ends 9 and 10, of lazy tongs, 11, are pivotally connected. The outer ends of said lazy tongs are attached pivotally to a signaling element, 12, shown in the form of the human hand. It will be noted that said outer ends of said lazy tongs are attached at different positions, as at 13 and 14, on said signaling element for the purpose of turning said signaling element from the vertical position, shown in Fig. 5, to the outwardly extended position as the lazy tongs are operated to move the signaling element outwardly to its different positions, as indicated in the broken line positions. One end thereof is provided with a link, as at 13^a, whereby the movement is to swing the signal element 12 on the pivotal connection at 14, as it moves outwardly, as will be clear from Fig. 5.

This construction avoids the cam action used in my former inventions and greatly simplifies and cheapens the construction without detracting from the accuracy and efficiency of the device. The discs, or operating elements, 2 and 3, are provided with springs, as 15, by which they are normally turned to the positions which return the signaling element 12 back in the case, 1, when

released by the operating cables 5, in a manner to be described. The operating cables run over pulleys, 16 and 17, in the case 1, as indicated in Fig. 5, and thence to other 5 pulleys, 18 and 19, on a bracket, 20, on the front of the automobile, through which said cables 5, 5, are extended and provided with finger rings, 21 and 22, for convenient operation. Two rocker or locking fingers, 23, 24, 10 are mounted on the bracket 20, as shown in Fig. 2, the fingers of which wedge said operating cables 5, against the sides of the bracket 20, for holding said cables against return movement under the action of the 15 springs, 15, before referred to, until released. Said holding fingers, 23 and 24 are yieldingly held in locking positions by means of a spring 25, as indicated. A trip lever or member, 26, is pivotally mounted through 20 the front of the machine and adapted, when depressed, to move the locking fingers 23 and 24, to release the cables 5, as will be clear from Figs. 2 and 3, whereupon the 25 springs 15 automatically operate to draw the lazy tongs 11 and signaling element 12 back into the case, and take up the cables 5.

In Fig. 1 I have also shown a foot operating lever, 27, connected by means of a rod, 28, to said trip lever, 26, for releasing the 30 same with the foot, if desired.

I have also shown a rear sight mirror, 29, mounted on the front of the case 1, where desired.

Thus I have greatly simplified and improved my invention and provided means for moving the signaling hand or element, 12, to the properly extended position, as in the case of the human arm signal now used. I have also provided said hand with means 35 for illuminating the same, as by means of phosphorescence coating, as indicated at 30, Fig. 5, although other illuminating means can be used, if desired. I do not, therefore, limit my invention to the showing made, 40 except as I may be limited by the appended claims.

I claim:

1. In a signaling device of the character referred to, in combination, supporting 50 means, lazy tongs, two movable operating elements pivotally connected to the inner ends of said lazy tongs adapted to support and operate the same, means for actuating said operating elements separately or together to extend said lazy tongs outwardly in three different directions, a signaling element pivotally connected to the outer ends of said lazy tongs, the pivotal connections thereto being adapted to automatically 55 swing said signaling element from a vertical position to a position longitudinally of the extended lazy tongs, substantially as shown.

2. In a signaling device, in combination, 60 a case, two operating elements therein to turn on a bearing, lazy tongs the ends of

which are connected respectively to said operating elements, said lazy tongs being wholly supported and operated thereby, a signaling element pivotally connected to the outer ends of said lazy tongs at two fixed locations, whereby to turn said signaling element from an upright position to an outwardly directed position as said lazy tongs are extended, and means for operating said operating elements separately or together for 70 extending said lazy tongs to any one of three different positions.

3. In a signaling device, in combination, a case, two rotatable elements mounted on a common bearing, lazy tongs having the 80 inner ends pivotally connected to said rotatable elements, means for rotating said rotatable elements separately or together to extend said lazy tongs in any one of three 85 extended positions, means for automatically returning said elements to normal positions when released, and a signaling element pivotally connected to the outer ends of said lazy tongs, one pivotal connection being adapted to move around the other relatively 90 as said lazy tongs are extended and to swing said signaling element from an upright position to an outwardly extended position as said lazy tongs are extended and to return the same as said lazy tongs are retracted. 95

4. In combination with lazy tongs, of rotatable operating elements connected thereto, operating cables for said rotatable elements, springs for normally returning said 100 rotatable elements to their normal positions, holding means for automatically holding said cables in extended position, and means for releasing said holding means to permit return movements.

5. In combination with lazy tongs and 105 means for extending and retracting the same, of a signaling element pivotally connected to the outer ends thereof, said signaling element being pivoted at two points to the end members of said lazy tongs, one of said pivot 110 points being adapted to move around the other as said lazy tongs are extended, to turn said signaling element from one position to another as it is extended.

6. In combination with lazy tongs and a 115 signaling element pivotally connected to the outer ends thereof, of means for operating said lazy tongs comprising two rotatable members, the inner ends of said lazy tongs being pivotally connected, respectively, to said rotatable members, operating means connected, respectively, to said operating members for rotating the same in opposite directions separately or together to extend said lazy tongs in any one of three different 120 extended positions, means for holding said lazy tongs extended, and means for normally returning the same.

7. In a signal device, in combination, lazy 125 tongs, a signaling element pivotally con-

nected to the outer ends of the outer end members thereof, the pivotal connections to said signaling element being in alinement with each other longitudinally of said signaling element, whereby the outer pivotal point moves around the inner pivotal point as said lazy tongs are extended to turn said signaling element outwardly, two rotatable operating elements to which the inner ends 5 of said lazy tongs are pivotally connected, springs for automatically returning said operating elements to normal positions when released, operating cables for turning said rotatable operating elements together or 10 separately in opposite directions, locking means operating on said cables to automatically grip and hold the same in extended positions, and means for releasing the same at will, substantially as described.

20 8. In a signaling device of the character

referred to, in combination, lazy tongs, a signaling element pivotally connected to the outer end members of said tongs, said pivot points being in fixed locations and spaced apart longitudinally of said member, whereby said member is turned about one of said pivot points as said lazy tongs are extended and retracted, two rotatable members pivotally connected, respectively, to the inner end members of said tongs, means for turning said members separately and together in opposite directions to extend said lazy tongs, and means for returning said rotatable members to their normal positions.

Signed at Los Angeles, California, this 35
14th day of August, 1922.

FREDERICK M. BALDWIN.
